UNITED STATES PATENT OFFICE.

JAMES COOK, SR., JAMES COOK, JR., AND JOHN COOK, OF LONDON, ENGLAND.

SEWING MACHINE.

Application filed October 25, 1924. Serial No. 745,850.

To all whom it may concern:

Be it known that we, JAMES COOK, Sr., JAMES COOK, Jr., and JOHN COOK, all subjects of the King of Great Britain, and all 5 residents of London, England, have invented certain new and useful Improvements in Sewing Machines, of which the following is a specification.

This invention relates to improvements in 10 sewing machines and relates more particularly to an improved combination of parts or mechanisms for operating the feed of the work and whereby a reduction of friction and a consequent increase of speed are obtained.

According to this invention, the main or lower shaft is provided with two cams or eccentrics, one for lifting and the other for traversing the feed-dog, the lifting cam being adapted to engage and rotate in an eccentric strap which is furnished with a slide or block adapted to move vertically in a fixed guide or distance piece, the said block being also furnished with a stud or pivot, 20 while the other cam, which is for traversing the feed-dog is rotatable in a hole in a slide vertically movable in a guide in the feed carrier or fork which is pivotally mounted at its lower end and rocks on the 25 stud or pivot. The main shaft is preferably mounted on ball bearings and the crank and connecting rod or link for driving the rocking shaft for the needle-bar are also similarly provided.

30 And in order that the invention may be readily carried into effect reference will be made to the accompanying drawings illustrating one embodiment of a sewing machine constructed according to this invention, and in which:—

Figure 1 is a part sectional elevation of the machine.

Figure 2 is an end elevation of the main shaft and connected parts.

45 Figure 3 is a section on the line III—III, Figure 1, and

Figure 4 is a section on the line IV—IV, Figure 1.

50 In carrying the invention into effect according to the construction illustrated and which is particularly suitable for machining hats, usually called a cylinder-arm chain-stitch machine, the bed *a* is of hollow and approximately semi-cylindrical cross section open at the bottom and furnished at each end with ball-bearings *b* and *c* respec-

tively for the main shaft *d*. The connecting rod *e* between the crank on the said shaft *d* and the arm or lever *f* on the rocking shaft *g* mounted in the arm *h* of the machine, is 60 also similarly provided at each end with a ball bearing or as shown there may be a ball bearing *i* surrounding the crank-pin *k* only.

Near the left hand end of the main shaft *d* furnished with the hook and looper (not 65 shown) the said shaft is furnished with two cams or eccentrics marked *l* and *m*, respectively, and set at an angle to each other and with a space between to accommodate a fixed plate or distance-piece *n* which is 70 mounted within the flanges of a cover *o* fixed to the distance piece *n* by screws *p* (Figure 2). The cam *m* is for raising and lowering the feed-dog and the cam *l* operates to cause the feed dog to reciprocate 75 transversely. The fixed plate *n* is secured in place by screws *q* engaging in another plate *2* to be presently described. The said plate *n* has a guide constituted by a vertical oblong slot *r* having parallel sides, the slot 80 being adapted to receive a small block or slide *s* integral with or, as shown, pivoted to a hollow stud *t* furnished with a head or shoulder at its outer end and mounted so as to project on one side of the lower end 85 of the rod *u* of an eccentric strap or feed lifting bar consisting of a more or less oblong piece of metal having a round hole near the top to engage the lifting eccentric or cam *m*. The hollow stud *t* on which the 90 block or slide *s* is mounted, is fixed to the feed lifting bar *u* by a grub screw *v* and is, furthermore, adapted to constitute the pivot of a fork-shaped feed-carrier *w*. This feed-carrier is furnished at the top with a slot *x* 95 having parallel sides and a small slide *y* of rectangular shape is adapted to slide freely in the guide or fork so formed. This small slide *y* is also provided with a round hole adapted to fit easily on the eccentric or cam 100 *l* for traversing the feed-dog. The effect of the two rotating cams *m* and *l* will be to cause the feed dog, which is fixed to the top of one of the fork members or prongs 105 of the feed-carrier *w*, to rise and descend and at the same time to move transversely to feed the work over the needle plate *z*. A steel plate *2* previously referred to, serves to take up any wear of the feed lifting bar *u* which may be caused by the thrust from 110 the feed-carrier *w*, and the plate is conveniently secured to the end of the bed *a* of the

machine by, say, three screws 3, of which one is shown in Figure 1 and the other two in Figure 4. If desired, the cap *o* is furnished with a low wall 4 to form a sump 5 for oil, the feed-lifting bar is provided with a hole 5 indicated in dotted lines in Figure 4 and containing a piece of wick to lubricate the stud *t* and the cam *m*. Similarly, the feed-carrier is provided with a hole 6, shown in dotted lines in Figure 2 and also containing a piece of wick for lubricating the slide *y*. If desired, one side or both sides of the cap *o* may be provided with a small hinged door (not shown) to give access to the interior for the removal of fluff or other foreign bodies without necessitating the removal of the cap and so possibly displacing the wicks from the sump.

I claim:—

20 1. In a sewing machine, the combination with a shaft, a cam mounted on the latter for imparting vertical movement, and a second cam mounted on the shaft for imparting traversing movement to the device 25 for feeding the material to be sewn, of a feed lifting bar mounted on the first cam, a stud on the said feed lifting bar, a fixed vertical guide in which the stud is adapted to reciprocate vertically, a feed carrier pivotally mounted on the said stud, and a guide on the said feed carrier within which the second cam is rotatable to cause the feed carrier to oscillate.

2. In a sewing machine, the combination 35 with a shaft, a cam for imparting vertical movement and a second cam for imparting traversing movement mounted on the said shaft of a feed lifting bar, co-acting with the lifting cam, a stud on the said feed 40 lifting bar, a slide freely mounted on the said stud, a fixed guide in which the said slide is adapted to reciprocate vertically, a feed-carrier pivotally mounted on the stud on the feed-lifting bar, a guide in the said 45 feed-carrier and a second slide adapted to slide in the guide of the feed-carrier and adapted to be reciprocated therein by en-

gaging with the traversing cam for imparting oscillating movement to the feed-carrier.

3. In a sewing machine, the combination with a shaft, a cam mounted on the said shaft and a second cam mounted on the said shaft and angularly in relation to the first cam, of a feed lifting bar co-acting with the first cam, a stud on the said feed lifting bar a slide freely mounted on the said stud, a vertical guide fixed to the bed of the machine and in which the said slide is adapted to reciprocate, a feed-carrier pivotally mounted on the stud on the feed lifting bar, a guide in the said feed-carrier and a second slide adapted to slide in the guide of the feed-carrier and adapted to be reciprocated therein by engaging with the traversing cam for imparting oscillating movement to the feed-carrier.

4. In a sewing machine, the combination with a bed, a main shaft, a cam mounted on the said shaft at the end of the bed where the needle plate is situated, a second cam mounted on the said shaft and angularly in relation to the first cam, a plate fixed to the bed of the machine between the two cams a ball-bearing for the shaft mounted in a hole 75 in the said plate and a ball-bearing at the other end of the shaft mounted in the bed of the machine, of a feed lifting bar co-acting with the first cam, a stud on the said feed lifting bar a slide freely mounted on 80 the said stud, a vertical guide in the fixed plate and in which the said slide is adapted to reciprocate, a feed-carrier pivotally mounted on the said stud on the feed lifting bar a guide in the said feed-carrier and a second slide adapted to slide in the guide 85 of the feed-carrier and adapted to be reciprocated therein by engaging with the second cam for imparting oscillating movement to the feed-carrier.

JAMES COOK, SEN.
JAMES COOK, JUNIOR.
JOHN COOK.
